J. H. WIGGINS

LIQUID STORAGE TANK

Filed Oct. 12, 1925

UNITED STATES PATENT OFFICE.

JOHN H. WIGGINS, OF BARTLESVILLE, OKLAHOMA.

LIQUID-STORAGE TANK.

Application filed October 12, 1925. Serial No. 62,019.

This invention relates to liquid storage tanks of the type in which the closure for the tank consists of a floating deck or roof that rests upon the body of liquid in the tank.

In the operation of filling a tank of the general type above referred to it frequently happens that gases become entrained with the liquid being pumped into the tank, and upon being liberated in the tank, rise upwardly through the liquid and escape either around the peripheral edge of the floating deck or through vents in said deck, thus causing liquid to be splashed over the top surface of the deck.

The main object of my present invention is to provide a means of simple construction for preventing liquid from being splashed onto the top surface of the deck by escaping gases. To this end I have devised a floating deck or roof for liquid storage tanks which is equipped with one or more devices constructed so that gases can escape through same from the underside of the deck, but any liquid entrained with said gases or combined with said gases in such a way as to produce a mechanical mixture of gas and liquid will be separated from the gases and recovered before said gases reach the atmosphere. The combined vent and separating device just referred to is preferably constructed so as to cause the separated liquid to be returned to the tank, and the floating deck is preferably constructed in such a manner that any mechanical mixture of gases and liquid produced in the tank will be bound to flow to the vent device or devices, instead of escaping around the edge of the deck.

Figure 1 of the drawings is a top plan view of a liquid storage tank equipped with a floating deck constructed in accordance with my present invention; and

Figure 2 is an enlarged vertical transverse sectional view, taken on the line 2-2 of Figure 1.

Referring to the drawings which illustrate the preferred form of my invention, A designates the side wall of a liquid storage tank, and B designates a floating deck or roof that rests upon the liquid α in said tank. The deck B is of slightly less diameter than the side wall A of the tank so that said deck can rise and fall as the level of the liquid in the tank varies, and the annular space between the peripheral edge of said deck and

the side wall of the tank can either be left open or closed by a means that protects the contents of the tank from the atmosphere and prevents gases and vapors from escaping from the tank through the annular space between said deck and tank side wall.

In the form of my invention herein illustrated the floating deck B is provided at its peripheral edge with a vertically-disposed, annular rim C whose lower edge portion terminates at a point considerably below the deck B, so as to virtually act as a baffle that prevents gases on the underside of the deck from bubbling up around the peripheral edge of the deck. If desired, the deck B can be bowed downwardly slightly from its peripheral edge towards its center, as shown in Figure 2, so as to form an annular gas pocket on the underside of the deck in proximity to the depending lower edge portion of the rim C, that is used to collect gases on the underside of the deck. The tank is provided with a filling pipe D that discharges into the tank adjacent the center of the bottom thereof, as shown in Figure 2. In the operation of filling the tank with oil gases usually become entrained with the oil, thus producing a mechanical mixture of liquid and gases, and rise upwardly through the oil, as shown in Figure 2, finally coming in contact with the underside of the deck B and being deflected by same towards the baffle formed by the depending lower edge portion of the rim C at the peripheral edge of the deck.

In order to separate the liquid phase from the gas phase and permit the gases to escape from the tank, without liability of causing the globules of oil to be splashed over the top side of the deck B, I provide the deck with one or more combined gas vent and liquid separating devices, each of which is indicated as an entirety by the reference character E. Said devices E can be constructed in various ways without departing from the spirit of my invention, but in the form of my invention herein illustrated each of said devices comprises a gas vent 1 mounted on the deck B at such a point that gases on the underside of the deck mixed with globules of oil can escape upwardly through said vent, as indicated in Figure 2, and a liquid and gas separating chamber 2 into which said gas vent 1 discharges. The upper end of the chamber 2 is open or is in communication with the atmosphere, and the gas vent

1 is of substantially inverted U shape in general outline and is arranged with the discharge end of same positioned inside of the separating chamber 2. Consequently, if 5 globules of liquid are entrained with the gases that escape from the underside of the deck through the gas vent 1, said liquid will separate from said gases upon entering the chamber 2, due to the greater specific 10 gravity of said liquid, and to the fact that the mixture of gases and liquid is subjected to a baffling action in traveling through the gas vent 1, and is then discharged downwardly into the separating chamber 2 from the down turned terminal end portion of 15 the gas vent 1. The gases, upon being separated from the liquid, immediately escape to the atmosphere through the open upper end of the separating chamber 2, as indicated in Figure 2, and the separated liquid is preferably returned to the liquid in the tank through a tube 3 that projects downwardly from the separating chamber 2 through the deck B, as shown in Figure 2. 20 25 In order to eliminate the possibility of gases on the underside of the deck B passing upwardly through the tube 3 into the separating chamber 2, instead of passing upwardly through the vent 1, the tube 3 is so proportioned that the lower end of same terminates at a point considerably below the intake end of the vent 1.

While I prefer to arrange a plurality of 30 combination vent and separating devices E 35 adjacent the peripheral edge of the deck B and construct said deck so that any gases liberated in the body of liquid in the tank will tend to collect on the underside of the peripheral portion of said deck, this particular 40 location of the devices E and particular construction of the deck B are not essential, as my invention, broadly stated, consists in equipping a floating deck or roof for a liquid storage tank with a gas vent through 45 which gases escape from the underside of the deck, and a separating chamber combined with said gas vent in such a manner that any liquid entrained with the escaping gases will be separated from same in said chamber and the cleaned gases thereafter permitted 50 to escape from said chamber.

Having thus described my invention, what I claim as new and desire to secure by Letters Patent is:

55 1. In a liquid storage tank provided with a floating deck, means for preventing the liquid in the tank from being carried out of the tank with escaping gases, comprising a gas and liquid separating device, and a 60 vent pipe leading to said device, said separating device being connected to the deck in such a way that the separated liquid is returned to the tank.

65 2. A liquid storage tank provided with a floating deck or roof supported by the liquid

in the tank, a gas vent on said deck through which gases mixed with globules of liquid can escape from the underside of the deck, and a device for separating said globules of liquid from the gases and for returning said 70 globules to the tank.

3. A liquid storage tank provided with a floating deck or roof that is supported by the liquid in the tank, a means which tends to cause gases that are liberated in the liquid in the tank to collect on the underside of the deck in a certain zone, and combination gas vent and liquid separating devices mounted on the deck in proximity to said zone for effecting the separation of any liquids entrained with the gases and for permitting the gases to escape from the tank without liability of splashing liquid onto the top surface of the deck.

4. A floating deck or roof for liquid storage tanks provided with a gas vent through which gases mixed with liquid can escape from the underside of the deck, said vent having a downwardly-projecting terminal portion, and a separating chamber into which gases are discharged from said vent, said separating chamber being provided with a gas outlet and also with a liquid outlet.

5. A floating deck or roof for liquid storage tanks provided with a liquid separating device consisting of a chamber arranged on the top side of the deck and provided with a gas outlet that leads to the atmosphere and a liquid outlet that leads to the underside of the deck, and a gas vent on said deck communicating with the underside of the deck and constructed so that gases which escape through same will be discharged into said chamber in a direction that tends to cause any liquids entrained with said gases to separate from same.

6. A floating deck or roof for liquid storage tanks provided with a gas vent through which gases mixed with liquid can escape from the underside of the deck, a separating chamber on the upper side of the deck provided with a gas outlet, a liquid outlet leading from said chamber to the underside of the deck and terminating at a point considerably below the inlet end of said gas vent, and means for causing the gases to be discharged from said vent into said chamber in a direction tending to cause the liquids entrained with said gases to separate from same in said chamber.

7. A floating deck or roof for liquid storage tanks provided with a gas vent of substantially inverted U shape in outline arranged so that gases mixed with liquid, can escape through same from the underside of the deck, and a separating chamber in which the down turned discharge end portion of said gas vent is arranged.

8. A floating deck or roof for liquid storage tanks provided with a gas vent of sub-

stantially inverted U shape in outline arranged so that gases mixed with liquid, can escape through same from the underside of the deck, a separating chamber in which the

5 down turned discharge end portion of said gas vent is arranged, the upper end of said chamber being open to the atmosphere, and a liquid outlet leading from the lower end of said chamber to a point below the under-

10 side of the deck.

9. A floating deck or roof for liquid storage tanks provided adjacent its peripheral edge with a downwardly-projecting, submerged baffle for preventing gases mixed 15 with liquid which collect on the underside of the deck from bubbling up around the peripheral edge of the deck, and a combination gas vent and liquid separating device arranged on the upper side of the deck at a

20 point in proximity to said baffle.

10. A floating deck or roof for liquid storage tanks provided at its peripheral edge with a vertically-disposed rim whose lower edge portion terminates at a point consider- 25 ably below the underside of the deck, the deck being bowed downwardly towards its

center, and combination gas vent and liquid separating devices on the top side of the deck arranged adjacent said rim, for the purpose described.

30 11. A floating deck or roof for liquid storage tanks provided with means for preventing gases from bubbling up around the peripheral edge of the deck, gas vents on the deck arranged in proximity to a zone where gases combined with globules of liquid tend to collect on the underside of the deck, and devices combined with said gas vents for causing said globules of liquid to be separated from the escaping gases and there- 35 after be returned to the liquid in the tank.

12. In a liquid storage tank provided with a floating deck, means for preventing the liquid in the tank from being carried out of the tank with escaping gases, comprising 40 a gas and liquid separating device, and means for causing escaping gases that contain entrained liquids to enter said device, said device being combined with the deck in such a way that the liquid separated from the 45 gases will be returned to the tank.

JOHN H. WIGGINS.
